UNITED STATES PATENT OFFICE.

LOUIS H. HARTMAN, OF PITTSBURGH, PENNSYLVANIA, ASSIGNOR OF ONE-HALF TO CHARLES A. COPELAND, OF PITTSBURGH, PENNSYLVANIA.

DESIGN FOR A PACK OF GAME-CARDS.

58,749.

Specification for Design. Patented Aug. 30, 1921.

Application filed April 27, 1921. Serial No. 465,002. Term of patent 14 years.

To all whom it may concern:

Be it known that I, LOUIS H. HARTMAN, a citizen of the United States, residing at Pittsburgh, in the county of Allegheny and State of Pennsylvania, have invented a new, original, and ornamental Design for a Pack of Game-Cards, of which the following is a specification, reference being had to the accompanying drawing, forming part thereof.

The invention comprises an ornamental design for a pack of game cards comprising fifteen cards, each card bearing thereon a representation of a colored pool-ball.

The figures are plan views of five cards showing my new design.

I claim:

The ornamental design for a pack of game cards, as shown.

LOUIS H. HARTMAN.
